UNITED STATES PATENT OFFICE.

GIUSEPPE GIOIOSA, OF EAST BOSTON, MASSACHUSETTS.

SAND-DISTRIBUTING MACHINE.

No. 796,203.

Specification of Letters Patent.

Patented Aug. 1, 1905.

Application filed January 14, 1905. Serial No. 241,031.

To all whom it may concern:

Be it known that I, GIUSEPPE GIOIOSA, a citizen of the United States, residing at East Boston, in the county of Suffolk and State of Massachusetts, have invented new and useful Improvements in Sand-Distributing Machines, of which the following is a specification.

This invention relates to an improved mechanism for distributing sand upon railroad-tracks in advance of the wheels of the car to prevent said wheels from slipping upon the rails.

Said invention is an improvement upon the device for feeding sand to railroad-tracks invented by me, for which Letters Patent of the United States were issued to me December 6, 1904, No. 776,782, and the general construction and operation of the device of this invention is substantially the same as the invention of said Letters Patent No. 776,782.

The object of this invention is to provide means for thoroughly drying the sand and keeping it heated, so that it will not freeze and so that it will flow freely downwardly from the chute from the sand-receptacle and be delivered in front of the wheels of the car upon the track.

The invention consists in the combination and arrangement of parts set forth in the following specification, and particularly pointed out in the claims thereof.

Referring to the drawings, Figure 1 is a side elevation of a portion of a car with my improved sand-distributing mechanism attached thereto. Fig. 2 is a central longitudinal section, partly in elevation, of the same. Fig. 3 is a transverse section, partly in elevation, taken on line 3 3 of Fig. 2. Fig. 4 is a detail section taken on line 4 4 of Fig. 2.

Like numerals refer to like parts throughout the several views of the drawings.

In the drawings, 5 is a portion of a car of any desirable construction, 6 the truck, and 7 the floor of the car.

8 is a receptacle for the sand, made, preferably, of sheet metal, being cylindrical in form and fastened by brackets 9 9 to a base 10. In the interior of the receptacle 8 is a partition 11, consisting of an inverted cone provided with an aperture 12 at the bottom thereof. Said partition divides the interior of said sand-receptacle 8 into two chambers—an upper chamber 13 and a lower chamber 14. The sand-receptacle 8 opens at its lower end through an aperture 12 into an aperture 15,

formed in the bottom plate 16. The sides of the aperture 15 are closed by flanges 17 17, projecting upwardly from the base 10, and beneath the aperture 15 is located a slide 18, having a hole extending therethrough, and beneath the slide 18 is attached a chute 20, which is connected by a coupling 21 to the under side of the base 10, the interior of said chute being in alinement with the hole 22, formed in said base 10.

The slide 18 is guided in ways 23, formed in the base 10, and is moved toward the right, Fig. 2, by springs 24 and toward the left by a segmental gear 25, which meshes into a rack 26, formed upon said slide, and is pivoted at 27 to a bracket 28, fast to the base 10. The segmental gear 25 is provided with a projecting arm 29, integral therewith, said gear and arm forming together a segmental gear-lever, the arm 29 being connected by a link 30 to a treadle 31, pivoted at 32 to a bracket 33, fast to the under side of the platform 7. The treadle 31 is pushed downwardly by a pin 34, which is depressed by the motorman whenever it is desired to distribute sand upon the tracks.

The sand contained in the receptacle 8 is agitated and thoroughly stirred by means of an agitator 35, consisting of a hollow arm 36, fast to the top of the slide 18 and extending upwardly therefrom through the aperture 15 in the bottom plate and into the interior of the receptacle 8 and in alinement with the hole 19, extending through said slide. Said agitator is provided with apertures 37, extending therethrough and connecting the interior of the same with the interior of the chamber 13. The top of said agitator is also left open to communicate with the interior of the upper chamber 13. In the lower chamber 14 is located a device for imparting heat to the sand, consisting, preferably, of a coil of wire 38, heated by an electric current. Said lower chamber is provided also with apertures 39 and is connected by a passage 40, formed in the slide 18, to the interior of the agitator 35.

The partition 11 is formed, preferably, of corrugated sheet metal, said corrugations being illustrated in detail in Fig. 4 of the drawings, the object of these corrugations being to allow the dry heated sand at the bottom of the mass of sand in the receptacle to follow the spaces between said corrugations and be guided by them downwardly through the apertures 37 to the interior of the agitator 35.

The depressions formed by the corrugations upon the under side of the partition 11 are preferably filled with portions of the heating-coil 38, so that said corrugations are at all times thoroughly heated, and the sand coming into contact with the convex upper side of said corrugations is kept dry and free from moisture, so that it will readily feed, guided by said corrugations, downwardly in the spaces between said corrugations upon the upper side of the partition 11 through the apertures 37 to the interior of the agitator 35, and thence falling downwardly will pass through the apertures at the bottom of the partition 11, through the aperture in the slide 18, and thence downwardly through the chute 20, to be finally delivered upon the rails in front of the car-wheels.

The general operation of the device hereinbefore described is as follows: Assuming the receptacle 8 to be filled with sand to a point above the conical partition 11 and the parts to be in the position indicated in Fig. 2, if the motorman desires to distribute sand upon the rail he presses his foot upon the pin 34, depressing the treadle 31 at the left-hand end thereof and raising the same at the right-hand end thereof. At the same time through the link 30 the segmental gear-lever and segmental gear 25, together with the arm 29, are rocked upon the pivot 27, moving the slide 18 toward the left from the position indicated in Fig. 2. Upon releasing the pin 34 the springs 24 will draw the slide 18 toward the right to the position shown in Fig. 2. During this reciprocatory motion imparted to the slide 18 the heated air in the lower chamber 14 is forced through the passage 40 to the interior of the agitator 35 by the air which rushes in through the apertures 39 by reason of the motion of the car. Said air thus rushing through the apertures 39 forces the air in the lower chamber 14 through the passage 40 and outwardly through the top of the agitator and through the apertures 37 in said agitator, thus drying and warming the sand as the agitator passes therethrough.

It will be understood that the heating-coil 38, located in the concavities formed in the under side of the partition by the corrugations 41, also dries and thoroughly heats the sand adjacent to the corrugated partition 11, and as said sand is dried adjacent to said partition it passes downwardly into the spaces between the corrugations 41 upon the upper side of the partition 11 into the interior of the agitator and downwardly through the chute 20, as hereinbefore described. It is very essential in a device of this character that the sand should be thoroughly heated, dried, and agitated in order that the same may flow down the chute to the track upon a single motion of the pin 34, hereinbefore described.

While I have described a heated electric coil

as being preferably used for a heating device in this connection, it is evident that a steam-coil or hot-water coil may be used if more convenient or desirable.

Having thus described my invention, what I claim, and desire by Letters Patent to secure, is—

1. In a sand-distributing machine, a receptacle for sand provided with an aperture in the bottom thereof, a slide located beneath said aperture and having a hole extending therethrough, a chute beneath said slide, mechanism to impart a reciprocatory motion to said slide, and a hollow agitator fast to said slide, in alignment with said hole and extending upwardly therefrom through said aperture and into the interior of said receptacle, said agitator provided with apertures connecting the interior thereof with the interior of said receptacle.

2. In a sand-distributing machine, a receptacle for sand comprising a hollow body, a base fast thereto provided with an opening extending therethrough, an inverted conical partition formed of corrugated sheet metal, said corrugations extending from the base of said cone toward the apex thereof, said partition located inside said body portion and dividing the interior thereof into an upper and a lower chamber, said partition provided with an aperture at the bottom thereof, and a device for imparting heat to said sand located in said lower chamber.

3. In a sand-distributing machine a receptacle for sand comprising a hollow body, a base fast thereto provided with an opening extending therethrough, an inverted conical partition located inside said body portion and dividing the interior thereof into an upper and a lower chamber, said partition provided with an aperture at the bottom thereof, and a device for imparting heat to said sand located in said lower chamber, a portion of said heating device located in and extending longitudinally of depressions formed by corrugations in the under side of said partition.

4. In a sand-distributing machine, a receptacle for sand comprising a hollow body, a base fast thereto provided with an opening extending therethrough, an inverted conical partition located inside said body portion and dividing the interior thereof into an upper and a lower chamber, said partition provided with an aperture at the bottom thereof, and a device for imparting heat to said sand located in said lower chamber; in combination with a slide located between said aperture and opening, and a hollow agitator fast to said slide and projecting upwardly therefrom through said aperture and into said upper chamber.

5. In a sand-distributing machine, a receptacle for sand comprising a hollow body, a base fast thereto provided with an opening extending therethrough, an inverted conical partition located inside said body portion and di-

viding the interior thereof into an upper and a lower chamber, said partition provided with an aperture at the bottom thereof, and a device for imparting heat to said sand located in said lower chamber; in combination with a slide located between said aperture and opening, a hollow agitator fast to said slide and projecting upwardly therefrom through said aperture and into said upper chamber, said slide provided with a passage connecting the interior of said agitator to said lower chamber.

6. In a sand-distributing machine, a receptacle for sand comprising a hollow body, a base fast thereto provided with an opening extending therethrough, an inverted conical partition located inside said body portion and dividing the interior thereof into an upper and

a lower chamber, said partition provided with an aperture at the bottom thereof, and a device for imparting heat to said sand located in said lower chamber; in combination with a slide located between said aperture and opening, and a hollow agitator fast to said slide and projecting upwardly therefrom through said aperture and into said upper chamber, said agitator provided with apertures connecting the interior thereof with said upper chamber.

In testimony whereof I have hereunto set my hand in presence of two subscribing witnesses.

GIUSEPPE GIOIOSA.
